CHEMICAL PROCESS AND PRODUCT

Frederick W. Breuer, Haverford, Pa., assignor to
The United Gas Improvement Company, a cor-
poration of Pennsylvania

No Drawing. Application June 25, 1942,
Serial No. 448,435

7 Claims. (Cl. 260—680)

This invention pertains generally to the preparation of unsaturated hydrocarbons and pertains particularly to the preparation of unsaturated hydrocarbons of the allenic type.

It has been known to the prior art (Paul and Hilly, Comptes Rendus 206, 608, 1930, and Bull. Soc. Chim. (5), 6, 218, 1939) that the triple bond between 2 carbon atoms can be reduced to the double linkage, if catalytic iron, prepared from aluminum iron alloys preferably of 10 to 30% by weight of iron content, by the method of dissolving the bulk of aluminum selectively, is applied as hydrogenation catalyst.

It has now been discovered that in the hydrogenation of olefin acetylenes of the type

over said iron catalyst 1,2 diolefins instead of 1,3 diolefins are formed. This mode of hydrogen addition could not have been predicted on the basis of the known art.

The formation of 1,2 diolefins from said types of olefin acetylenes is best explained by the mechanism of 1,4 addition, the resulting compounds being of the allenic type.

The reaction may be represented by the following equation:

each of R_1 , R_2 , R_3 , and R_4 being either hydrogen or an organic radical, for example, an alkyl radical.

In the case of monovinyl acetylene the equation

represents the reaction.

Regardless of the correctness of the above hypothesis allenic types, previously obtainable only through a series of involved reactions have become readily available by the above described invention.

The following examples will serve to further illustrate the invention.

Example 1

Iron catalyst is prepared by treating an iron aluminum alloy of preferably 10 to 30% by weight of iron content in essentially the same way as in the well known preparation of Raney nickel catalyst. Because of the high degree of reactivity with water the active iron is left in contact with aqueous solvents for a minimum length of time

only, and is immediately transferred to a non-aqueous dispersing agent, such as ethyl alcohol.

The catalyst and monovinyl acetylene are placed with or without the addition of polymerization inhibitor in a suitable pressure hydrogenation apparatus. Hydrogenation is carried out at elevated temperatures and pressures, temperature ranges of 60 to 100° C. and pressures of 400 to 800 pounds per sq. in. being particularly suited for the process. The hydrogenation reaction is best stopped when the calculated quantity of hydrogen has been absorbed. Following customary technique for the isolation of the product a satisfactory yield of butadiene 1,2 (methyl allene) is obtained. This hydrocarbon boils at 10° C. in accordance with the literature data and is further identified by its tetra bromide.

Example 2

20 Iron catalyst is prepared from 46 g. of powdered iron aluminum alloy of the composition of 10% Fe and 90% Al by weight. This alloy is added slowly and with stirring to a solution of 184 g. of sodium hydroxide in 200 cc. of boiled out water, the temperature of the mixture not being permitted to rise above 90° C. The addition of the alloy required 2½ hours. The mixture is placed on a water bath for one hour and after decanting a solution of 184 g. of sodium hydroxide in 200 cc. of boiled out water is again added to complete the dissolution of the bulk of the aluminum. After a period of concentration of one and one half hours the black iron powder is permitted to settle and the supernatant solution is decanted. The iron precipitate is washed three times with boiled out water, transferred to a filter and washed with boiled out water until the washings are neutral towards phenolphthalein. The active iron is then washed with 95% ethyl alcohol and finally washed with absolute alcohol. It is suspended in 70 cc. of absolute ethyl alcohol.

Freshly distilled monovinyl acetylene (26 g.= 0.5 mole), and the iron catalyst prepared according to the description presented above, are placed in a suitably cooled pressure vessel equipped for shaking and heating, and are subjected to a hydrogen pressure of 560 lbs./sq. in. (gauge) measured at 23° C. and heated with shaking.

The temperature is gradually increased with corresponding increase in hydrogen pressure from 23° C. to approximately 110° C. over a period of approximately 7 hours.

The unabsorbed hydrogen is then released, care

being taken to collect in a dry ice cooled trap any volatile reaction products. The hydrogenation bomb is cooled to approximately -50° C. and its contents recovered completely by washing twice with each 25 cc. 95% ethyl alcohol. The iron catalyst is separated from the solution of the reaction products by filtration. The solution (112 cc.) contains unreacted monovinyl acetylene as evidenced by a test with silver nitrate.

Upon fractionating through a fractionating column of an efficiency equivalent to say 13 theoretical plates a fraction of butadiene-1,2 (4.14 g.) boiling between 8 to 10° C. at atmospheric pressure, is obtained.

It will be understood that the foregoing is by way of illustration.

Examples of polymerization inhibitors for use for example, as in Example 1, are as follows: p-tertiary butyl catechol, quinone, hydroquinone, and p-aminophenol.

Other changes, omissions, additions, substitutions and/or modifications may be made within the scope of the claims without departing from the spirit of the invention which is intended to be limited only as required by the prior art.

I claim:

1. A process for producing a compound of the formula

wherein each of R_1 , R_2 , R_3 , and R_4 is one of a group consisting of hydrogen and an alkyl radical comprising hydrogenating in the presence of an activated iron catalyst a compound of the formula

wherein each of R_1 , R_2 , R_3 and R_4 has the same meaning as before.

2. A process for the manufacture of butadiene-

1,2 comprising hydrogenating monovinyl acetylene in the presence of an activated iron catalyst prepared by dissolving the bulk of aluminum from an iron aluminum alloy.

5. 3. A process for producing a compound of the formula

comprising subjecting a compound of the formula

to hydrogenation conditions in the presence of an activated iron catalyst.

4. A process for preparing butadiene-1,2 comprising hydrogenating monovinyl acetylene in the presence of an activated iron catalyst prepared by dissolving the bulk of aluminum from an iron aluminum alloy, said hydrogenation being carried out at elevated temperatures and pressures in the presence of a polymerization inhibitor.

20 5. A process for the manufacture of butadiene-1,2 comprising hydrogenating monovinyl acetylene in the presence of an activated iron catalyst obtainable by dissolving the bulk of aluminum from an iron aluminum alloy, said hydrogenation being carried out at elevated pressures.

6. A process for the manufacture of butadiene-1,2 comprising hydrogenating, at elevated pressures and temperatures, monovinyl acetylene in the presence of an activated iron catalyst obtainable by dissolving the bulk of aluminum from an iron aluminum alloy.

30 7. A process for the manufacture of butadiene-1,2 comprising hydrogenating monovinyl acetylene over an activated iron catalyst obtainable by dissolving the bulk of aluminum from an iron aluminum alloy, said hydrogenation being carried out in the presence of a polymerization inhibitor.

FREDERICK W. BREUER.
